ELECTROMAGNETIC PICKUP UNIT

Ronald J. Rockwell, Cincinnati, Ohio

Application June 25, 1949, Serial No. 101,344

4 Claims. (Cl. 179—100.41)

1

This invention relates to an electromagnetic pick-up unit for use with sound records, whereby stylus vibrations, caused by such records, are transformed to corresponding electrical manifestations, and the invention more particularly pertains to such a pick-up unit that is adapted for use with sound records of either the lateral cut or vertical cut type. The pick-up unit employs a single loop of non-magnetic, electrically conducting material, this loop functioning as the sole support for a stylus and also as the support for a magnetic member mounted for movement within a coil. When the pick-up is employed with laterally cut records, electrical currents representative of the sound modulation are induced by the movable magnetic element in the coil, the leads of the coil being brought out to terminals. Additionally, the loop is disposed between the poles of a fixed magnet, so that it serves as a conductor element, in which current is induced, when the loop is employed with vertically cut records. Further the coil may be arranged in series circuit with the loop itself, during use with laterally cut records, so that the electrical output is furnished by both the loop and the coil, the loop moving relative to the fixed magnet and the movable magnet moving relative to the coil.

It has long been an objective in the sound reproduction art to provide a mechanically movable magnet support for an electromagnetic pick-up which is light and, therefore, requires very small forces to move it, which responds with high fidelity to the entire range of sound modulation, and which is free of the collateral noise and distortion generally attributable to natural vibration frequencies.

I have devised such a light weight, low-inertia magnet support embodying these desirable features. The device employs a single loop of electrically conducting, non-magnetic material which supports a magnetic member extending within a coil, the loop having secured thereto a stylus adapted to sense the sound records with which it is to be used and to transmit mechanical movement to the loop and magnetic member. The novel loop is made of lap-seamed tubular material formed into a long narrow U-shaped configuration, said loop being supported by its legs. The bight of the loop holds the stylus, and rocking movement of the stylus or axial movement of the stylus, causes the loop to twist or flex. During rocking movement of the stylus the movable magnetic member moves in the coil and generates an electric current. Inasmuch as the material of which the loop is made is of an open lap-seamed

2

construction, and, as the loop is made of an open lap-seamed construction, and, as the loop is long and narrow, the loop is easily twisted on its longitudinal axis and is flexible out of the plane of the loop, but strongly resists flexing within the plane of the loop. Such action of the loop structure is utilized so that the twisting of the loop occurs when the stylus is rocked by laterally cut records and the flexing of the loop occurs when the stylus is axially shifted by vertically cut records.

When the pick-up is employed with laterally cut records, the electrical signals induced in the coil are brought out from a pair of terminals. Additionally the loop itself, as stated above, is disposed between the poles of a fixed magnet and forms a part of a second electrical circuit, which may be connected in circuit with the coil.

When the pick-up is employed with vertically cut records, the coil is not used. The two ends of a loop then function as one terminal and a flexible wire connection attached to the bight of the loop functions as the other terminal.

The loop is constructed of light, strong and flexible metal, forming with the stylus and movable magnetic member the only movable mass, which mass is of low inertia and highly responsive to stylus vibrations. The extreme ease with which the loop can be twisted and flexed, and its light mass, permit the stylus to follow high frequency vibrations with great fidelity. Although any light, strong, flexible, non-magnetic electrical conductor may be used for the loop, I preferably choose an aluminum alloy including, approximately, 0.5 per cent of magnesium, 0.5 per cent manganese, 4 per cent cooper, 94 per cent aluminum, and traces of iron and silicon. For a stylus I propose to use any commercially useful stylus, but prefer to use either an aluminum tube tipped with a sapphire point or an osmium rod having a stylus point contour on one end. I also use various acoustic damping materials, which are selectively placed at points tending to vibrate resonantly, for the purpose of preventing collateral noise.

It will be apparent that my electromagnetic pick-up unit is eminently useful in the playing of temporary, fragile or soft recordings, as well as ordinary commercial records, yet furnishing a reproduction of high fidelity over the entire useful audible sound range, free of disturbances caused by resonance vibrations of the part, such results being attributable to the novel materials and structures used in the construction of the

Therefore, the principal object of my invention is to provide a novel electromagnetic sound pick-up head of the type comprising a magnetic member moved relative to a coil by a stylus, in accordance with the sound modulations of a record disc.

Another object of the invention is to provide such an electromagnetic pick-up device wherein the loop, supporting the magnetic member, is made of tubular material formed in a long narrow U-shaped configuration.

Another object of the invention is to provide such a pick-up device wherein the tubular material of such support contains a longitudinally-lapped-seam disposed on the inner aspect of the U-shaped formation.

Another object of the invention is to provide such an electromagnetic pick-up device in which the loop, supporting the stylus and the magnetic member, is made of a high strength, flexible aluminum alloy.

Another object of the invention is to provide such an electromagnetic pick-up in which such loop is made of an electrically conducting, non-magnetic tubular material.

Another object of the invention is to provide such an electromagnetic pick-up device in which the conductive loop consists of a single U-shaped turn disposed in a single air gap between two poles of a permanent magnet, so that both the loop and the coil can be used to develop the induced currents representative of the sound modulations during use with laterally cut records.

Another object of the invention is to provide such a device in which the legs of the loop are employed to develop the induced currents when sensing vertically cut records.

For a better understanding of the present invention, together with other and further objects, capabilities and advantages thereof, reference is made to the accompanying drawings wherein there is shown an illustrative form of pick-up in accordance with the invention.

In the drawings:

Fig. 1 is a side elevation of the novel device, showing its disposal within a case which is shown in section.

Fig. 2 is a section through the device of Fig. 1, on the line 2-2 thereof.

Fig. 3 is a perspective view of a portion of the permanent magnet as looked at from the rear face, showing the disposition of the loop between the pole pieces thereof and the disposition of acoustical damping material between the pole pieces and the loop.

Fig. 4 is a perspective view of the loop, parts being broken away to show the internal disposition of the elements.

Fig. 5 is an enlarged perspective view of the ends of the loop, showing the lapped-seam construction thereof, and showing the plastic material filling the open seams.

Fig. 6 is a perspective view, with certain parts broken away, of the rear end of the novel pick-up device as removed from the casing.

Fig. 7 is a side elevation of the pick-up device as removed from the casing.

Fig. 8 is a bottom plan view of the device as removed from the casing.

In the drawings, the same reference numerals refer to the same parts throughout the several views and the sectional views are taken looking in the direction of the arrows at the ends of the section lines.

All of the elements of the present pick-up with the exception of four are shown and described in my co-pending United States patent application, Serial Number 739,246, filed April 3, 1947, entitled "Electromagnetic pick-up unit," now U. S. Patent No. 2,478,712, granted August 9, 1949, and assigned to the same assignee as the present invention and application. Reference is made to said co-pending patent application for a complete and specific description of those elements. The four elements, which are not common to both applications are: movable magnetic element or member 10, a coil 11 and a pair of terminals 12 and 13 to which the leads of the coil are connected. The present invention resides in the provision of these additional elements and the resultant novel combinations and sub-combinations. Accordingly that portion of the description immediately following, with the exception of the discussion of these four elements, is substantially a duplication of descriptive material contained in the aforementioned co-pending patent application.

I employ a permanent fixed magnet 20 of approximately square block proportions. The magnet has a rear face 21 (Fig. 3), a front face 22 (Fig. 2) and a passageway 23 extending from the rear face to the front face and opening downwardly to form the legs of a rectangular U-shaped magnet. I prefer to use a fixed magnet of approximately .4 inch in length between the front face and the rear face, approximately .4 inch in height between the top of the magnet and the bottom of the legs thereof, and approximately .4 inch in width between the sides thereof, with an air gap passageway having a height of approximately .25 inch and a width of about .15 inch. For the magnet material I prefer to use an aluminum-nickel-cobalt-iron alloy. On the bottom of each leg of the magnet is soldered, or otherwise fastened, a magnet-steel pole piece, said pieces 24 and 25 being each approximately .06 inch in thickness, each of said pole pieces being flush on the side and rear faces of the magnet with the edges of the magnet, each of said pole pieces extending slightly toward the interior of the passageway from the walls of the passageway so as to leave an air gap therebetween of about .093 inch; and each of said pole pieces extending approximately .2 inch in front of the front face of the permanent magnet, said forwardly projecting portions of the pole pieces being shaded to blunt points 26 and 27 as shown in Fig. 8. In this relatively long and narrow air gap, between the interior edges of the pole pieces, the electric conductor loop, to be described, is disposed. Soldered, or otherwise fastened, to the rear face of the magnet is a brass plate 30 (Figs. 6 and 7) having a rearwardly extending step 31, the bottom of which step is in the plane of the bottom of the legs of the fixed magnet. Brass plate 30 has an aperture 14 therein, which is the size of the passageway 23 opening in the magnet at its rear end and continuous therewith.

The rearwardly extending step 31, of plate 30, is slightly narrower in width than the vertical portion which is soldered to the rear magnet face 21. This plate 30 and its rearwardly extending step 31 act as a standard brace for holding the electrical loop conductor in the air gap between the pole pieces of the magnet, and for holding a rigid conductor, used when vertical cut records are sensed, which conductor extends through the upper part of the passageway between the legs of the magnet.

75 Referring especially to Figs. 3, 4, 5 and 6, I

provide tubular conductor loop 32, which, preferably, is made of the aluminum alloy mentioned previously, from sheet material approximately .0025 inch in thickness, rolled into a lapped-seamed tube having an internal diameter of approximately .01 inch, making the tubing have a minimum diameter of about .015 inch. The tube form is seen best in Fig. 5 where the ends of the conductor loop are shown. It will be seen that the tubing is lap-seamed with an overlap of approximately 30° of the circumference, although such angle is not extremely critical. Filling the seam is plastic acoustical damping material 33 which, preferably, is a nitrocellulose-camphor product plasticized with castor oil or tricresyl phosphate and dissolved in acetone for application, so that such material, upon the drying of the acetone, assumes a tacky viscous state in which it prevents resonance vibration of the tubing without substantially interfering with the twisting and flexing action, to be described.

Referring to Fig. 4, the tube 32 is bent into a long narrow U-shaped formation, preferably, with the seam on the inner aspect of said U-shaped formation, the space between the parallel legs of the U being approximately .03 inch. As the bight formed by the tight bend of the loop has a very small radius, the tubing may be collapsed at the bend, if desired. The U-shaped formation forms an electrically conductive loop which is disposed in the air gap between the magnet pole pieces so as to very nearly, but not quite, touch the inner edges of said pole pieces when said U-shaped loop is twisted on its long axis or flexed upwardly and downwardly in a vertical manner. The space between the loop and the inner edges of the pole pieces and the space between the legs of the loop, is filled with a damping material, which preferably is a dimethyl-silicon-oxide polymer material containing a soap to form a viscous mass. For the purpose of decreasing the effective mass of the damping material it may be mixed with wood pulp, that being made of balsa wood being most desirable because of its low density. This damping material 34 is shown in Fig. 3.

In the bight end of the loop is cemented a stylus 35 which, when the unit is placed in its casing presents a downwardly pointing record engaging end as shown in Figs. 1 and 2. By reference to Figs. 1, 2 and 3 it will be seen that the conductor loop is so disposed in the air gap that its plane is horizontal, and, hence, when the stylus engages laterally cut horizontally disposed disc sound records the loop will be twisted on its long axis by the sound track, and, when the stylus is used with vertically cut horizontally disposed disc sound records, the stylus will respond vertically and flex the loop upwardly and downwardly in the air gap. In the former circumstance, the two ends of the loop form two terminals to complete the usual electric circuit of the sound translating device. In the latter case the two ends of the loop are used as one terminal and the front, bight end, of the loop is used as the other terminal for completing the electric circuit of the sound translating device.

I provide pins 36 and 37 (Fig. 4) made of stiff electrically conducting material, such as steel wire, for insertion in the open ends of the tube, said pins being snugly fitted therein. The pins by their insertion into the tube have several functions. One of these functions is to act as a tuning means, whereby the natural vibration frequency of the loop may be adjusted by moving

the pins, or either of them in or out of the tube. Another function of these pins is to act as internal supports so that the ends of the tube may be clamped in a clamping means for supporting the loop in the air gap, as will be described, without crushing the tube ends. A third function of these pins is to act as terminals to which electric conductors may be easily soldered when it is desired to connect the device to the electric circuit in which it is used. It will also be apparent that the internal ends of the pins which extend beyond the clamp act as cantilevers and prevent breaking of the tubes on the clamp edge.

Referring to Fig. 6, I provide a Phosphor bronze clamp 40 by which the loop conductor 32 is held securely against the bottom of the step 31, with a sheet of mica 41 insulating the loop from the step 31, and a sheet of mica 42 insulating the loop from the clamp. On top of the step 31 is a sheet of mica 43 on which is placed a rigid Phosphor bronze ribbon conductor 44 which is in turn covered by a sheet of mica 45 held in place by a Phosphor bronze plate 46. The ears 47, 48 of the clamps, are bent over to clamp the conductors tightly in place.

It will be seen, from Fig. 6, that the pins 36 and 37 are free for soldering electric terminals thereto, as is the end of conductor 44. Conductor 44 has a forwardly extending portion which is bent angularly upwardly and then horizontally so that it passes through the passageway between the legs of the magnet near the top thereof. This conductor 44 extends slightly beyond the front face of the magnet as seen in Fig. 1 and is electrically connected to the front end of the loop by wire 51 which is made, preferably, of yielding wire about .003 inch, or less, in diameter, so that vertical or twisting movement of the loop, as it is distorted by the sound records, will not be impeded by any stiffness thereof. As seen in Fig. 1, the conductor loop 32 is given a slight downward set, when it is being secured in the clamping means, in order that when the stylus is placed on a sound record and the effective weight of the pick-up device and associated holding arms come to bear thereupon, the conductor loop will be straightened so as to assume a horizontal position in the mid-line point of the pole pieces between the legs of the fixed magnet. If such original downward set to the loop were not provided, the weight of the pick-up device and associated supporting arm structure would bend the loop upwardly out of the field of greatest magnetic density.

Soldered to plate 39 (Figs. 6 and 7) is a Phosphor bronze strip 60 having a rearwardly extending portion 61 which may be used as an electric terminal for grounding purposes.

Referring to Figs. 1 and 2, I provide a casing within which the pick-up device may be mounted, 60 said casing being made of light weight non-magnetic material. The casing has a top 70, sides 71 and 72, a downwardly sloping front section 73, a vertical front section 74, and a bottom closure plate 75 containing an aperture 81 through which the point of the stylus protrudes. On each of the side walls 71 and 72, in the rear part of the casing, is secured a flat plate which extends slightly inwardly of the inner wall of the casing. As shown in Fig. 1, plate 76 on wall 72 extends nearly to the top 70 leaving a space 77, which acts to provide a ledge-like slot between the top edge of the plate 76 and the top 70, which accommodates one edge of a lock-nut plate 78. The forward end of the plate abuts against the plate 30 of the magnet. As the same provision is made on the

side piece 11, and as lock-nut plate 78 is made large enough to extend across the interior width of the casing, the said nut plate may be slid in and out between said side plates and the top of the casing. Lock-nut plate has threaded holes therein to receive locking bolts such as bolt 79, by which the bottom plate 75 is secured in place. In assembly of the device the lock-nut plate 78 is slid in place through the open bottom of the casing, the pick-up device assembly is placed in the casing with the top of the magnet against the top of the casing. The forward upper edge of the magnet is positioned at the corner between the top and portion 73 of the casing and the rear of the magnet is held by the side plates described.

As the bottom plate 75 is put in place, the stylus projects through the hole 81, and the bottom plate securely holds the magnet between it and the top of the casing. Thus the pickup unit is held in assembly.

Suitable terminal couplings may be provided whereby the device is slipped onto a pickup device holding arm, to complete electrical connections to an electrical signal translating device in the usual manner.

If desired, an insulating sleeve, such as sleeve 80 (Fig. 1) made of woven fabric or molded tubing, may be provided for the conductor 44 to prevent accidental contacts thereof with the magnet.

It will be understood that the tubular loop construction, which I provide, is unusually strong for its dimensions, and is especially resistant to resonance vibration interfering with the fidelity of reproduction of the sensed sound record. The loop is damped by reason of the acoustical plastic material provided in the open seams of the tube, and by the selective use of the viscous material between the sides of the loop and the edges of the pole pieces, and between the legs of the loop.

It is also apparent that where I have specified Phosphor bronze, aluminum alloy, and the like, equivalent materials having similar characteristics may be used without in any way departing from the spirit of the invention. Moreover, although I have specified certain dimensions as desirable for use with the materials preferred, which give unusually good results, such dimensions and characteristics may be varied somewhat according to the effects desired.

One of the most important features of this pick-up device is its light weight as a whole, and in the extreme flexibility, lightness and strength of the moving subassembly therein. Inertial effects damaging to the recording medium, and tending to distort the recorded sound have, by this invention, been reduced to a minimum.

In accordance with the present invention I provide a movable magnetic member, a stationary electrical coil adapted to be placed in inductive relation to said movable magnetic member, and an electrically conductive loop member for supporting both the vibratory member and said movable magnet, said conductor comprising a piece of open lap-seam tubing of a U-shape form. Specifically there is attached to the legs of the conductive loop 32, as by a flexible glue, a movable magnetic member 10 which may be made of the same material as magnet 20. This upwardly extending member projects into a coil 11, composed of insulated wire disposed within passageway 23. The torsional movement of the support 32, when the pick-up is employed with laterally cut records, causes a turning movement of the magnetic member 10, relative to the axis of coil 11, whereby there are induced in coil 11 electric currents re-

presentative of the sound modulation. The insulated leads of coil 11 are brought out to a pair of terminals 12 and 13, those terminals comprising a pair of flat strips of metal projecting forwardly to a point near aperture 14. When laterally cut records are employed the output electrical signals may be taken from terminals 12 and 13 alone, the voltage output being relatively high because of the plurality of turns of wire on coil 11. Alternately one voltage output may be taken from terminals 12 and 13 and another voltage output may be taken from terminals 36 and 37, the latter being described in the aforementioned co-pending patent application. These voltage outputs may be taken in series. Therefore, the invention also provides a loop of the character described, which functions not only as a stylus support and as an electrical conductor which has electrical current induced in itself by the fixed permanent magnet, but also as a support for moving the movable magnetic member relative to a fixed coil.

During operation with vertically cut records the magnetic member 10, the coil 11, and the terminals 12 and 13 are not employed, the latter then being simply disconnected from the circuit. The operation for vertically cut records is precisely as described in my said co-pending patent application.

It will be seen that an improvement which is provided by the present invention over and above the basic arrangement shown in my said co-pending patent application, resides in the use of loop 32 as a support for a movable magnet, which functions to induce current in a coil 11, having a large number of terminals as compared to the loop itself, whereby a relatively high voltage output may be obtained.

The coil 11 may be secured within passageway 23 by its own expanding forces or otherwise suitably secured in place. Movable magnet 10 is preferably a flat, thin, light rectangular shaped permanent magnet. Terminal strips 12 and 13 are secured between mica strips 43 and 45 and may be made of the same materials as terminal strip 44.

While there has been shown and described what is at present considered to be the preferred embodiment of the present invention, it will be obvious to those skilled in the art that various modifications and changes may be made therein without departing from the true scope of the invention as defined in the appended claims.

Having fully disclosed and described my invention, I claim:

1. Vibration translation apparatus comprising a stylus, a stationary coil, a movable magnetic member for inducing currents in said coil, an electrical conductor for supporting said stylus and said magnetic member, said conductor comprising a piece of open lap-seamed tubing of a U-shaped loop form, means for mounting said loop for torsional flexure, and means for mounting said coil.

2. In a pick-up device the combination of a stylus, an electrical conductor, a movable magnetic member in inductive relation to said conductor, a distortable support for said stylus and said magnetic member, said support comprising a long U-shaped loop of open lap-seamed tubular non-magnetic metal, a clamp in which the legs of the loop are mounted in contact with the clamp so the loop may be twisted on its long axis, or bent out of its plane, but which resists distortion in its plane, and means for mounting said con-

ductor in proximity to said magnetic member so that currents are induced in said conductor.

3. In a pick-up device, the combination of field-producing means including a pair of poles arranged to form a single long narrow air gap, a stylus, a U-shaped conductive support for said stylus, said support comprising a tube of metallic non-magnetic material having a lapped longitudinal seam on the interior of the U-shaped tube, the legs of the U being substantially parallel and slightly separated, the U formation fitting within the air gap along its length and in inductive relation to the field-producing means but without touching said poles and the free ends of the U extending slightly at one end of the gap, a non-conductive bracket holding the extending free ends of the U, whereby the support forms a loop that may be twisted and flexed in the air gap, a movable magnetic member secured to said support, a stationary coil, and means for mounting said coil so that said movable magnetic member projects into the coil, both said support and said coil having electric currents induced therein when said stylus tracks laterally modulated sound record discs.

4. An electromagnetic pick-up device cooperative with stylus vibrating types of sound records, including in combination, a long narrow U-shaped electrical conductor made of flexible tubular material and having an open lap-seam, means for holding the free ends of the U-shaped conductor insulated electrically, a fixed magnet having opposed pole pieces forming a long narrow air gap, said holding means disposing the U-shaped conductor along said air gap and spaced slightly from but inductively related to the poles, substantially in the region of greatest magnetic density, and a stylus held in the bight end of the U-shaped conductor so that rocking the stylus twists said conductor and so that axial movement of said stylus flexes said conductor out of its normal plane, whereby to cut the lines of magnetic force, a coil fixed-secured to and insulated from said fixed magnet and a movable magnetic member projecting into said coil, said movable magnetic member being secured to said U-shaped conductor.

RONALD J. ROCKWELL.
